ELECTRICALLY OPERATED TEXT WRITING DEVICE FOR BOOKKEEPING MACHINES

Franz Hübl, Göteborg, Sweden, assignor to Keinzle Apparate G. m. b. H., Villingen, Schwarzwald, Germany

Application September 20, 1955, Serial No. 535,334

Claims priority, application Germany October 4, 1954

6 Claims. (Cl. 197—18)

The invention relates to an electrically operated text writing device for bookkeeping machines.

Electrical typewriters are known, wherein the type striking operation is effected by the motor, the known pivotable type bars supported in segments being moved by rotary cams associated with each key and each type bar respectively. Such devices result in appliances too intricate for motorized manual typewriters.

In order to obtain a simple and inexpensive construction with reliable effect, a rotary motor driven type wheel is provided which is stopped, in the respective positions corresponding to the selected keys by means of stops operated by pressure on the respective keys, and is caused to strike. In an advantageous embodiment, cams are mounted on a shaft. The shaft is driven by a slip clutch through a gear wheel actuating the type wheel and positioned on a pivoted lever carrying the type wheel. The cams are actuated by key operated stops in such manner that they stop the type wheel in a respective position, wherein the type corresponding to the pressed key is in printing position. The gear wheel journaled on the pivoted lever and the gear wheel mounted on the cam shaft are positioned so that their pitch circles extend in, a short distance from the pivotal axis of the pivoted lever. The direction of rotation of the gear wheel on the pivoted lever is such that after stopping the cam shaft the pivoted lever is swung in striking direction by the gear wheel on the pivoted lever rolling on the gear wheel on the cam shaft. To insure reliable performance of each operation (type print), a locking frame is provided catching the respectively pressed key in operational position. The locking frame is returned from the locking position by the pivoted lever e. g. by means of a pin thereon in the striking position of the pivoted lever.

An embodiment of the invention is shown in the drawing.

Fig. 1 is an end elevational view of the device according to the instant invention;

Fig. 2 is an elevational view of the device of Fig. 1;

Fig. 3 is a plan view of the device of Fig. 1; and

Fig. 4 is a side view of a portion of Fig. 1 in an operative engaging position.

Referring now to Fig. 1, below a printing spot of a platen 1, the pivoted lever 3 is journaled on an axis 2. A type wheel 4 is journaled on the pivoted lever 3. A shaft 6 with a gear wheel 7 is driven in direction of the arrow by a motor (not shown) through a slip clutch 5. This wheel drives a gear wheel 8, mounted on the type wheel 4, through gear wheels 11, 10, 9. The pivoted lever 3 is drawn into the position as shown by a spring 12. The gear wheel 11 also engages a gear wheel 15 securely mounted on a shaft 14 and to which its rotary movement is transmitted. The position of the gear wheels 11 and 15 is such that the two pitch circles extend in a short distance from the axis 2 so that the gear wheels 11 and 15 maintain engagement during swinging movement of the pivoted lever 3. As more clearly

2

shown in Figs. 2 and 3, each letter of the type wheel 4 has a corresponding stop 16 securely mounted on the shaft 14, and each stop 16 has a corresponding latch 17. The latches 17 are pivotally mounted on a shaft 18 and are each connected to a key 20.

On depressing a key 20, the associated latch 17 is moved into the path of its associated stop 16. The type wheel is stopped in such manner that the selected letter of the type wheel 4 is in printing position. The gear wheel 15 is locked, and since the gear wheel 11 continues to rotate, and that downwardly at its point of engagement with the gear wheel 15, it rocks the pivoted lever 3 in a clockwise direction. By this rocking movement the letter is printed.

The pivoted lever 3 carries on its lower arm 21 a pin 22 which, at the moment of printing, rocks a locking frame 23 to release the latch 17 which upon depression of the associated key had been held in position by the spring actuated locking frame 23. The spring 12 now returns the type wheel into position of rest. Since blocking of the gear wheel 15 is released and the slip clutch 5 pulls through, all wheels turn again till the next key is struck. Upon each stroke of a key an indexing device (here not shown) is actuated in a known manner for advancing the carriage.

In order to obtain straight line writing, a toothed correcting wheel 24 shown in Fig. 2 is mounted on the type wheel, the wheel being straightened by a centering element 25 positioned just in front of the printing spot.

What I claim as my invention and desire to secure by Letters Patent of the United States is:

1. In an electrical typewriter, the combination of a platen for the paper to be written upon; a type wheel bearing type characters; a lever pivotally mounted on a fixed pintle, biased to normal position, on which said lever is journaled, said roll and said platen being so relatively disposed that the wheel prints its characters upon the paper when said lever is rocked from its normal position; a drive shaft adapted to be electrically driven; a driven shaft; a sliding clutch connecting said shafts; a gear wheel fixed on said driven shaft; a second gear wheel journaled on said lever and meshing with said first gear wheel; a third gear wheel on said type wheel; a gear train on said lever, connecting said second and third gear wheels, whereby said type wheel is rotated by said driven shaft; a counter shaft; a fourth gear wheel fixed on said counter shaft, meshing with said second gear wheel, and adapted to rotate said counter shaft; a plurality of stops fixed on said counter shaft and corresponding with the type characters on said type wheel, respectively, said stops being moved in circular paths by rotation of said counter shaft; a plurality of latches adapted to co-act with said stops, respectively; and a plurality of keys corresponding with the type characters on said type wheel, and adapted to move said latches into the paths of rotation of said stops, respectively, to stop rotation of said counter shaft and said fourth gear wheel mounted thereon, said second and fourth gear wheels being so disposed relative to the pintle of said lever that, when rotation of said fourth gear wheel is stopped, said second gear wheel rolls on said stationary fourth gear wheel and thereby rocks said lever to cause said type wheel to move toward said platen to print the selected character on the paper on said platen.
2. An electrical typewriter, according to claim 1, having a locking frame pivotally mounted adjacent said latches, and biased to normal position to lock said latches in operative position, and a pin on said lever adapted to move said frame to unlock said latches.

3. In an electrically operated textwriting device for bookkeeping machines, the combination of a platen for the paper to be written upon; a type wheel bearing type

characters; a lever pivotally mounted on a fixed pintle; spring-means retaining said lever in normal, inoperative position, said type wheel being journaled on said lever, and said type wheel and said platen being so relatively disposed that the wheel prints its characters upon the paper when said lever is rocked from its normal position; driving means and toothed-wheel gearing means, the latter being disposed between said driving means and said type wheel; and means adapted to interrupt rotation of said type wheel when a selected character is positioned relative to said platen for printing said character, said toothed-wheel gearing means being adapted to transmit driving movement from said driving means to said type wheel and to transmit the effect of said interrupting means from the latter to said type wheel, said driving means and said interrupting means co-operating against the action of said spring-means to rock said lever to print said selected character.

4. In an electrically operated textwriting device for bookkeeping machines, the combination of a platen for the paper to be written upon; a type wheel bearing type characters; a lever pivotally mounted on a fixed pintle, biased to normal position, on which said type wheel is journaled, said wheel and said platen being so relatively disposed that the wheel prints its characters upon the paper when said lever is rocked from its normal position; a drive shaft adapted to be electrically driven; a driven shaft; a slip clutch connecting said shafts; a gear wheel fixed on said driven shaft; a second gear wheel journaled on said lever and meshing with said first gear wheel; a third gear wheel on said type wheel; a gear train on said lever, connecting said second and third gear wheels, whereby said type wheel is rotated by said driven shaft; a counter shaft; a fourth gear wheel fixed on said counter shaft, meshing with said second gear wheel, and adapted to rotate said counter shaft; and selectable interruption means adapted to interrupt rotation of said counter shaft in selected positions.

5. In an electrically operated textwriting device for bookkeeping machines the combination of a platen for the paper to be written upon; a lever pivotally mounted on a fixed pintle; spring means retaining said lever in a normal, inoperative position; a type wheel bearing type characters journaled on said lever, said type wheel and

said platen being so relatively disposed that the wheel prints its characters upon the paper when said lever is rocked from its normal position; means for interrupting rotation of said type wheel when a selected character is positioned relative to said platen for printing of said character on the paper; driving means; toothed wheel gearing means disposed between said driving means and said type wheel for transmitting driving movement to said type wheel and for transmitting the action of said interrupting means to said type wheel, said driving means and said interrupting means being adapted to co-operate against the action of said spring means to rock said lever to print said selected character; and means for insuring the correct position of said selected character relative to said platen during the printing thereof.

6. In an electrically operated textwriting device for bookkeeping machines the combination of a platen for the paper to be printed upon; a type wheel bearing type characters; a lever pivotally mounted on a fixed pintle; spring means for retaining said lever in a normal, inoperative position, said type wheel being journaled on said lever, and said type wheel and said platen being so relatively disposed that said wheel prints its characters upon the paper when said lever is rocked from its normal position; driving means and toothed wheel gearing means, the latter being disposed between said driving means and said type wheel; means for interrupting rotation of said type wheel when a selected character is positioned relative to said platen for printing thereof, said toothed wheel gearing means being adapted to transmit rotational driving movement from said driving means to said type wheel and also to transmit the action of said interrupting means from the latter to said type wheel, said driving means and said interrupting means being adapted to co-operate against the action of said spring means to rock said lever to print said selected character, and means for insuring the correct positioning of said selected character relative to said platen during the printing thereof.

UNITED STATES PATENT OFFICE
CERTIFICATE OF CORRECTION

Patent No. 2,870,897

January 27, 1959

Franz Hübl

It is hereby certified that error appears in the above numbered patent requiring correction and that the said Letters Patent should read as corrected below.

In the grant, lines 1 to 3, for "assignor to Keinzle Apparate G. m. b. H., of Villingen, Schwarzwald, Germany," read -- assignor to Kienzle Apparate G. m. b. H., of Villingen, Schwarzwald, Germany, --; Line 12, for "Keinzle Apparate G. m. b. H., its successors --; read -- Kienzle Apparate G. m. b. H., its successors --; in the heading to the printed specification, lines 4 to 6, for "assignor to Keinzle Apparate G. m. b. H., Villingen, Schwarzwald, Germany" read -- assignor to Kienzle Apparate G. m. b. H., Villingen, Schwarzwald, Germany --.

Signed and sealed this 23rd day of June 1959.
